(57) **CLAIM**

The ornamental design for a blood pressure monitor, as shown and described.

DESCRIPTION

FIG. 1 is a top view showing our new design for a blood pressure monitor;

FIG. 2 is a front view of the blood pressure monitor of FIG. 1;

FIG. 3 is a back side view of the blood pressure monitor of FIG. 1;

FIG. 4 is a bottom side view of the blood pressure monitor of FIG. 1;

FIG. 5 is a left view of the blood pressure monitor of FIG. 1;

FIG. 6 is a right view of the blood pressure monitor of FIG. 1; and,

FIG. 7 is a perspective view of the blood pressure monitor of FIG. 1.

The broken lines showing a cuff in connection with the blood pressure monitor are for illustrative purposes only and form no part of the claimed design.
